COMPLEX QUATERNARY AMMONIUM COMPOUNDS

John M. Tinker, Penns Grove, N. J., and Adrian L. Linch, Wilmington, Del., assignors to E. I. du Pont de Nemours & Company, Wilmington, Del., a corporation of Delaware

No Drawing. Application January 11, 1943,
Serial No. 472,000

7 Claims. (Cl. 260—482)

This invention relates to complex quaternary ammonium compounds, particularly adapted for use as surface-active agents, and processes for their production.

It is an object of this invention to produce a new class of quaternary ammonium compounds. A further object is to produce a class of compounds having appreciable value in the industrial arts generally and in the surface-active field particularly. A still further object is to produce these compounds in a simple and economical manner from readily available intermediates. A still further object is to produce compounds which may be used in place of or in admixture with soap and the numerous soap substitutes heretofore described in the literature. Additional objects will become apparent from a consideration of the following description and claims.

These objects are attained in accordance with the present invention wherein a halogenated aliphatic carboxylic acid ester and a trialkylamine are reacted at temperatures below about 35° C., the reaction being continued for a sufficient period of time to permit a further reaction between the quaternary ammonium compounds initially produced. In a more restricted sense this invention is concerned with a process wherein an alpha-halogeno-aliphatic carboxylic acid ester is reacted with a trialkylamine at temperatures within the range of about 0° C. to about 35° C., the reactants being maintained in contact with each other under the foregoing conditions for a sufficient period of time to permit a further reaction between the quaternary ammonium compounds initially produced. In a still more restricted sense this invention is directed to a process wherein esters of alpha-bromo-aliphatic carboxylic acids, which acids contain at least six carbon atoms, are condensed at room temperatures with low molecular weight trialkylamines in the presence of a polar solvent, the reaction being continued for a sufficient period of time to permit a further reaction between the quaternary ammonium compounds initially produced. In its preferred embodiment the invention is directed to the reaction at approximately room temperature of an ester of an alpha-bromo-aliphatic carboxylic acid, which acid contains from twelve to eighteen carbon atoms, with trimethylamine in the presence of a polar solvent such as methyl alcohol, the reactants being maintained in contact with each other under the foregoing conditions for a sufficient period of time to permit further reaction between the quaternary ammonium compounds initially produced. The invention is also concerned with products produced in accordance with the foregoing or equivalent processes. An additional

feature of the invention is the conversion of these complex quaternary ammonium compounds to derivatives thereof. Another feature is the employment of the foregoing and related products in the industrial arts and particularly in the soap substitute field.

The invention may be more readily understood by a consideration of the following illustrative examples wherein the quantities are stated in parts by weight.

In these examples an equation is given for the reaction which probably occurs, although it is to be understood that the invention is not to be restricted to the reactions set forth in these equations.

EXAMPLE I

168 parts of trimethylamine and 90 parts of methyl-alpha-bromo-caprylate were dissolved in 285 parts of methyl alcohol, and agitated at room temperature for 220 hours. After filtering from precipitated tetramethyl ammonium bromide, the filtrate was evaporated to a small volume by heating at 60–80° C. under reduced pressure. Sixty parts of dry acetone was added, the mixture chilled for several hours and filtered from tetramethyl ammonium bromide. The filtrate was diluted with 440 parts of benzene and 260 parts of solvent distilled out of the mixture to remove traces of water and trimethylamine. The residue on cooling deposited crystals, which were filtered off and crystallized from 100 parts of dry acetone. The crystals melted at 113–115° C. Further crystallization from dry acetone raised the melting point to 133–134° C.

Analysis

	Found	Theory	
45 Percent nitrogen.	5.75	5.63	(M. W.=497) $\text{C}_{21}\text{H}_{40}\text{O}_4\text{N}_2\text{Br}$
Percent bromine.	16.4	16.1	

EXAMPLE II

176 parts of trimethylamine and 107 parts of methyl-alpha-bromo-caprate were dissolved in 300 parts of methyl alcohol. After agitating for

162 hours at room temperature, the mixture was cooled to 10° C. and 68 parts of ether added. Tetramethyl ammonium bromide was removed by filtration and the filtrates evaporated to a small volume under reduced pressure at 35-50° C.

Then 63 parts of acetone and 54 parts benzene were added, the mixture chilled to -65° C. and the crystals filtered off. They were immediately crystallized from 88 parts of dry benzene, and then from 80 parts of dry acetone.

5 These ester derivatives are saponified by alkaline reagents. Thus the derivative from methyl-alpha-bromo-palmitate was saponified by boiling in 0.3 normal sodium hydroxide solution for 14 hours. The sodium salt recovered by evaporation and crystallization from acetone and methyl alcohol mixture melted at 190-193° C. and contained one-half atom of bromine per atom of nitrogen.

10

Analysis

	Found	Theory	
Percent nitrogen	5.03	5.08	(M. W. 553) C ₂₇ H ₄₇ O ₄ N ₂ Br
Percent bromine	14.58	14.52	
Melting range °C.	149-150		

From the filtrates from the preceding crystallizations, further quantities of the same product may be obtained.

EXAMPLE III

175 parts of methyl-alpha-bromo-palmitate was added to a solution of 220 parts of trimethylamine dissolved in 375 parts of anhydrous methyl alcohol. The mixture was agitated at 20-25° C. for 185 hours and then filtered to remove tetramethyl ammonium bromide, which crystallized during the reaction. The mother liquors were chilled and filtered from white crystals melting at 169-173° C. After crystallization from a mixture of 158 parts of dry acetone and 20 parts of absolute methyl alcohol, they melted at 180-183° C.

Analysis

	Found	Theory	(M. W. 408) for—
Per cent nitrogen	3.40	3.45	CH ₃ -(CH ₂) ₁₃ -CH-COOCH ₃
Per cent bromine	19.64	19.65	(CH ₃) ₃ N-Br

Additional product of the above constitution was obtained by working up the filtrates. The mother liquor from the above recovery was diluted with 440 parts of benzene, and 260 parts of solvent was distilled off to remove traces of water. Crystals which separated on cooling were filtered off and washed with dry, cold acetone. The product was crystallized from a mixture of 240 parts of acetone and 24 parts of methyl alcohol.

Analysis

	Found	Theory	
Per cent nitrogen	3.78	3.88	C ₁₉ H ₄₀ O ₄ N ₂ Br
Per cent bromine	11.8	11.1	
M. W. degrees	146-147		

Additional product may be obtained from the mother liquors.

Similar results were obtained with methyl esters of alpha-bromo-stearic-, alpha-bromo-lauric- and alpha-bromo-capric-acids. The alpha-chloro and alpha-iodo derivatives likewise produce analogous products.

EXAMPLE IV

22 parts of n-octyl-alpha-bromo-caprylate and a solution of 29 parts of trimethylamine dissolved in 52 parts of absolute methyl alcohol were agitated at room temperature (23-28° C.) for nine days. The mixture was chilled and filtered from tetramethyl ammonium bromide. The mother liquors were evaporated under reduced pressure, diluted with 80 parts dry acetone, chilled and an additional quantity of tetramethyl ammonium bromide filtered off. The filtrate was evaporated to dryness under reduced pressure, treated with 80 parts of petroleum ether, chilled, filtered and the product crystallized from a mixture of acetone and petroleum ether.

Analysis

	Found	Theory	(M. W. = 296) for—
Nitrogen	4.47	4.73	CH ₃ (CH ₂) ₇ -CH-COOCH ₃
M. P. °C.	153-155		(CH ₃) ₃ N-Br

40 The filtrate was evaporated under reduced pressure, and extracted with 300 parts of water. The extract was washed with 70 parts of ether, and evaporated under reduced pressure at 35-40° C. 350 parts of benzene was added and traces of water removed by distillation at 120-140° mm. 45 pressure and at 50° C. The crude product was crystallized from a mixture of ether and acetone and was identical with the product described in Example I.

50 Similar results are obtained by carrying out the reaction in ethyl, propyl, butyl and amyl alcohols to obtain the corresponding ester complexes by ester interchange during the reaction with trimethylamine. Other esters, for example propyl, amyl, hexyl, dodecyl, octadecyl, phenyl, cyclohexyl, etc., of alpha-bromo-aliphatic acids from butyric to montanic and higher acids undergo ester interchange when condensed with trimethylamine in an alcohol of different molecular weight than present in the original ester. It is 55 obvious that by employing the same alcohol for solvent and esterification the corresponding ester group will be present in the final condensation product.

EXAMPLE V

65 70 75 60 parts of anhydrous n-butyl alcohol (B. P. 118° C.), 5 parts of the product described in

Example III, and 0.05 part of lead oxide (litharge) were heated together at 60-65° C. for 3 hours. The pressure was reduced to 75-78 mm. and the methyl alcohol and excess butyl alcohol distilled off. The residue was twice crystallized from dry acetone and melted at 152-154°.

This ester interchange reaction may be applied to the synthesis of a variety of esters by employing other alcohols in place of n-butyl alcohol. Likewise, the products described in Examples I and II or other esters thereof may be employed as starting materials in this ester interchange with higher molecular weight alcohols.

It is to be understood that the foregoing examples are representative merely of a relatively few of the many embodiments of this invention. They may be varied widely with respect to the individual reactants, the amounts thereof and the conditions of reaction without departing from the scope hereof.

In place of or in addition to the halogenated aliphatic carboxylic acid esters referred to in the foregoing examples, numerous other compounds may be employed. These compounds are preferably esters of aliphatic carboxylic acids which acids contain six or more carbon atoms and advisably from twelve to eighteen carbon atoms. Esterification of such acids may be accomplished in accordance with well known procedure by treatment with various alcohols, either monohydric or polyhydric. The hydrocarbon radical of such alcohols is preferably, but not necessarily, an alkyl group of no more than twenty carbon atoms, although it may be cycloaliphatic and/or may contain alkoxy and/or halogen groups. The foregoing esters have substituted thereon a halogen atom which may be chlorine, bromine or iodine. Substitution may take place in various positions although for optimum results it is advisable that it be in the alpha position.

The hydrocarbon group of the foregoing acids and alcohols may be straight or branch chain and may contain one or more additional substituents which do not enter into or interfere with the reaction described herein.

The foregoing esters are reacted with a trialkylamine which is preferably of low molecular weight. Numerous well known trialkylamines, either alone or in admixture with one another, may be used for this purpose. Likewise, these amines may be further substituted provided that the substituent or substituents does not react with or interfere with the described reaction. A representative few of such amines are ethyl dimethylamine, hydroxy ethyl dimethylamine, di(hydroxy-ethyl)-methylamine and triethanolamine.

The foregoing reaction is advisably carried out in a polar solvent such as methyl alcohol, ethyl alcohol, water, etc.

As previously mentioned, one or more aliphatic acid esters and one or more trialkylamines may be employed to produce compounds of the desired character. The amounts of the individual reactants may vary widely although it is generally preferable to use a large excess of the trialkylamine. In the case of the solvent employed, the amount may vary widely but it is advisable to use sufficient thereof in order that the reaction mixture may be kept in a fluid state.

To produce the products described herein it is essential that the temperature of the reaction shall be kept below about 35° C. Temperatures of from about 0° C. to about 35° C. are satisfac-

tory and for most economical results temperatures approximating room condition should be employed. Temperatures above about 35° C. should not be used since they will prevent formation of the desired complex quaternary ammonium compounds. Temperatures below 0° C. are suitable but they usually require an excessive period of time to produce the desired results and for that reason, as well as the cost, are not fully recommended.

It is important that not only should the temperature be maintained within the foregoing range but sufficient time should be allowed to permit the initially formed quaternary ammonium compounds to react and produce complex derivatives of higher molecular weight. These derivatives generally contain two pentavalent nitrogen groups but they may be even more complex and contain three or more of such groups, depending upon the reactants, the temperature, and the time of reaction. In any event, they should contain no less than two pentavalent nitrogen atoms and for this reason the instructions previously given, particularly with respect to temperature and time, should be carefully followed.

Complex quaternary ammonium compounds produced in accordance with the instructions hereof may be further modified by condensation with primary or secondary aliphatic or aromatic amines to yield amide-like quaternary ammonium complexes. Amides of this type are likewise of considerable value in the industrial arts and for the most part exhibit unusual and valuable surface-active properties.

The products of this invention are characterized by excellent surface-active properties in aqueous solution. They are particularly good detergents in neutral, acid or alkaline mediums and in the presence of alkaline earth and heavy metal salts. In addition, these products give outstanding results as electroplating assistants, reduction of anti-freeze surface tension, foam promoters, dyeing assistants, vat dye retardants, leveling agents in dye baths, printing assistants, wool scouring agents, flotation assistants, wetting agents, emulsifying agents, dispersing agents for dyes, latex, clay, pigments, etc., softening and swelling agents for synthetic fibers, boiling off assistants for rayons, corrosion inhibitors and assistants in acid pickling baths, leather tanning assistants, etc.

As many widely different embodiments of this invention may be made without departing from the spirit and scope thereof, it is to be understood that the invention is not limited to the specific embodiments thereof except as defined in the appended claims.

We claim:

60. 1. A process which comprises mixing at temperatures within the range of about 0° C. to about 35° C. approximately two molar quantities of an alkyl ester of an alpha halogeno aliphatic carboxylic acid, said acid containing from six to eighteen carbon atoms, and approximately three molar quantities of trimethylamine in the presence of a polar solvent, said reaction being continued for a sufficient period of time to permit a further reaction between the quaternary ammonium compounds initially produced, then separating the excess trimethylamine from the resulting product.

65. 2. A process which comprises mixing at approximately room temperature approximately two molar quantities of an alkyl ester of an alpha

bromo aliphatic carboxylic acid, said acid containing from six to eighteen carbon atoms, and approximately three molar quantities of trimethylamine in the presence of a polar solvent, said reaction being continued for a sufficient period of time to permit a further reaction between the quaternary ammonium compounds initially produced, then separating the excess trimethylamine from the resulting product.

3. A process which comprises mixing at approximately room temperature approximately two molar quantities of an alkyl ester of an alpha bromo aliphatic carboxylic acid, said acid containing from twelve to eighteen carbon atoms, and approximately three molar quantities of trimethylamine in the presence of methyl alcohol, said reaction being continued for a sufficient period of time to permit a further reaction between the quaternary ammonium compounds initially produced, then separating the excess trimethylamine from the resulting product.

4. A process which comprises condensing at approximately room temperature approximately two molar quantities of methyl alpha-bromo-palmitate and approximately three molar quantities of trimethylamine in the presence of methyl alcohol, said reaction being continued for a sufficient period of time to permit a further reaction between the quaternary ammonium compounds initially produced, then separating

the excess trimethylamine from the resulting product.

5. Quaternary ammonium compounds represented by the following formula:

10 wherein R represents an alkyl group of four to sixteen carbon atoms, R₁ represents an alkyl group, and X represents a member selected from the class consisting of chlorine and bromine groups.

15 groups.
6. The quaternary ammonium compounds of
claim 5 wherein R represents an alkyl group of
ten to sixteen carbon atoms, R₁ represents an
alkyl group of one to eight carbon atoms, and
X represents bromine.

20 7. A quaternary ammonium compound having the following formula:

JOHN M. TINKER.
ADRIAN L. LINCH.
